UNITED STATES PATENT OFFICE

ALEXANDER NYMAN, OF DOBBS FERRY, AND WILLIAM DUBILIER, OF NEW ROCHELLE, NEW YORK, ASSIGNORS TO DUBILIER CONDENSER CORPORATION, OF NEW YORK, N. Y., A CORPORATION OF DELAWARE

CONDENSER

Application filed August 4, 1927. Serial No. 210,628.

This invention relates to electrical condensers, and particularly condensers designed primarily for use in communication by radio.

The structure of the condenser comprises a plurality of stacks or sections of alternating layers of conducting material and dielectric, arranged radially with respect to a common center or axis, and maintained in position under a required degree of compression.

10 This particular condenser is intended for use with short electric waves or oscillations, which cause the terminals to have relatively great tendency to heat. An object of the invention is to overcome this tendency by making almost the entire casing of the condenser consist of terminals, the base or body of the casing serving as one terminal and the cover or lid of the casing serving as the other.

20 A further object is to arrange certain external surfaces, as will be made clear in the description, to provide a surface path such as currents of this nature will preferably take.

25 A further object is to provide efficient insulation between the two large terminals by having part of the casing made of insulating material between the base and cover.

30 A number of other objects of the invention are secured by imparting a concavo-convex configuration to the exterior of the casing, adapted to permit the condensers to be nested or piled up in stacks when such a combination is desired and yet leave sufficient space inside for insulating purposes. The configuration in question is conducive to ease of 35 assembling and mounting the condenser in its ultimate operative location, and still further increases the ease with which the condenser radiates heat, even when not provided with all the features specifically mentioned herein. Also the necessity for long conducting strips to connect the interior sections with the exterior terminals is obviated by this concavo-convex configuration.

40 A still further object is to provide a strong compression ring, within which the stacks can be placed to form a sub-assembly unit prior to final assembly within the casing.

The drawings illustrate a preferred form of the invention; in which:

50 Figure 1 is a horizontal view of a condens-

er according to our invention partly in plan and partly in section on the dotted line 1—1 of Figure 2;

55 Figure 2 is a vertical cross section taken longitudinally of two opposed condenser sections or stacks;

Figure 3 is an exterior view, being a side elevation and on a somewhat smaller scale than Figure 2;

60 Figure 4 is a plan view of a contact plate for the condenser;

Figure 5 is a side elevation of said contact plate in finished form;

65 Figure 6 is a diagrammatic view showing the path of current through several of the condensers when nested, the condensers being taken in section along line 6—6 of Figure 1;

70 Figure 7 is a cross section in the same vertical plane as Figure 2 but shows one of the conductors modified;

75 Figure 8 shows part of Figure 7 enlarged; and

Figure 9 is a diagrammatic view showing the path of the current through the modified arrangement of Figure 7.

In the drawings the same numerals identify the same elements throughout.

80 A small boxlike metallic shell 1 constitutes half, more or less, of the outside casing. A plate 2, dish-shaped or concave, forms the lid or cover of the casing. Between the shell and cover a wide ring or short cylinder 3 of insulating material, such as glass, forms the greater part of the sides of the casing and thoroughly insulates the lid 2 from the shell or body 1. The casing surrounds and supports stacks or sections of condenser elements indicated generally by the numeral 4. Outside lugs 5, best shown in Figure 3, facilitate attachment of the adjacent condensers together in a stack and provide lead-in terminals or points of attachment of the electric conductors for the current, these lugs 5 being provided with perforations 6.

85 The four stacks of condenser elements are indicated individually by the numeral 7 and are pressed firmly against a central metal flat-sided block 8 by outside pressure plates 9. Each stack or body 7 comprises a num-

ber of units 11, each composed as usual of alternate layers of electrically conductive elements such as metal foil and of insulation such as mica. These units are spaced apart by separator blocks 10 consisting of a core of insulating material surrounded by a sheet of metallic conducting material. In the modification illustrated the units 11 are shown relatively thin and the separator blocks 10 relatively thick. The cover 2 of the casing is held in place by means of screws 12 threaded into holes tapped into the central block 8. An opening extending entirely through the condenser permits access of the outside air to the interior of this hollow block and introduces a cooling action at the center of the condenser where it is most needed.

Flange 57 at the interior end of the hollow block 8, and flange 58 at the center of the casing 1 serve to support a tube of insulation 56. Tube 56 is held in place by means of thread ring 61 engaging threads in casing 1. Gaskets 59 and 60 are located at the ends of the insulating tube. Holes 62 are provided in ring 61 for the application of a spanner wrench.

For assembling the four stacks in place, insulating blocks 14 are inserted to prevent access of current to the large mass of metal in the block 8, where it would set up eddy currents and produce heating. No attempt is made to insulate the block 8 from the terminal or cover 2, for mere voltage or electric potential is not objectional as it does not give rise to losses. Conductors 15 are placed adjacent the innermost element of each stack 7 to connect the inner end of each stack to a common plate 16 having flanges 17 thereon adapted to be soldered to these four conducting strips or plates 15 so as to conduct current between the inner ends of all four stacks and the lid 2. This lid 2 is provided with a depending lip or flange 18; and a soft gasket 19, the purpose of which is explained below, is placed between the part 3 and the cover, and is shielded by the flange 18.

The flexible metal conducting plates 20, shown in Figures 1 and 6, connect the outer ends of each stack to the main part of the casing 1. This casing 1 has a rim or outer flange 21 which surrounds a strong compression ring 22, and upon assemblage this ring 22 is fast to the casing 1 by means of screws 23. The ring 22 rests on a shoulder 24 with in the rim 21.

Other insulating blocks 25 are disposed at the outer ends of the stacks. These blocks 25 serve a purpose similar to that of the blocks 14, as they prevent a flow of current through the heavy masses of metal in the thrust blocks 9, with the consequent eddy currents and heating effects. No attempt is made to insulate thrust blocks from the voltage on the terminal or sheet 1.

Heavy pressure is exerted upon each of the

stacks by large screws 26 which pass through the ring 22 but are not threaded into the ring 22, being threaded instead into thrust blocks 27. These blocks distribute the stress a considerable way around the ring 22 and keep it from being localized at one point, which would be right at a place of special weakness; namely, where the hole is drilled to allow screw 26 to pass through. The inner ends of the screws are rounded to press against the blocks 9 by entering rounded recesses 28. Another advantage of having these screws threaded through separate blocks 27 instead of directly into the ring 22 is that, the ring may be distorted by the large forces slightly out of round, and in that case the threads would not pinch so as to prevent rotation of the screws. The outer ends of these screws are provided with the usual slots 29. The holes 30 in the ring 22, through which the screws 26 pass, are large enough to permit considerable relative movement of the thrust blocks 27.

Figure 1 of the drawings shows the ring 22 thickened out or strengthened midway of the thrust screws. This feature is not always essential. The ring is usually made of uniform thickness throughout and the resultant springiness is somewhat desirable as it keeps a continuous pressure on the stacks under varying temperatures. However, if in making some particular size or proportion of this condenser, such a uniform section of the ring proves unduly weak, then reinforcing or thickening midway of the thrust screws can be adopted. The ring is made of a non-ferrous metal, such as phosphor bronze, to avoid additional eddy currents that would creep in if a magnetic material were located so near the oscillating currents as this ring 22.

Having the ring 22 separate from the shell 1 permits the casing to be made of reasonably thin material. This could be accomplished by imbedding the heavy ring in a cast casing but such a method would not permit ease of assembling. After the sub-assembly within the ring is complete, the ring 22 is then fast to the body of the casing 1 by means of screws 23, thus making the ring rigid with the casing; and produces all the advantages that could be secured by embedding the ring into the shell 1 by casting the shell about the ring.

The casing may be filled with wax or other insulating material, poured into the casing in liquid form and allowed to harden and embed the sections 7 and other parts.

A gasket 31 of soft material, such as rubber, is introduced between the glass ring 3 and the ring 22. This bulges out sideways and prevents leakage of wax past the flange 21, as well as between the rings 3 and 22. The aperture closed by plug 32 permits filling with wax and the exit of air bubbles when the condenser is inverted with respect to the

position shown in the drawings. A gasket 33 between the plate 16 and the block 8 prevents leakage of wax from inside the casing into the central opening 13. The gasket 19 prevents leakage of wax past the top of glass cylinder 3 and the top 2.

The order of assembly is as follows:

The stacks are assembled within the ring 22, the end plates 15 being soldered to the flanges of plate 16. This subassembly is placed within the casing 1 and fastened by means of screws 23 on the shoulder 24. Gasket 31, insulating ring 3 and gasket 19 are then laid on, whereupon the cover or lid 2 is put on and fastened by means of screws 12. The compression of the gaskets 31 and 19 by means of screws 12 does not disturb or upset the stacks 7 because they are under relatively great pressure from the ring 22. Tube 56 and ring 61 are then assembled.

In order to permit nesting of a plurality of these condensers, the inside curve of the hollowed-out cover 2 is made on a contour of greater diameter than the outside curve of the convex bottom of the shell 1. This is to make sure that no ball-and-socket action takes place when a number of these condensers are stacked up. Moreover there are slight elevations 35, shown in Figure 3, on the shoulder 34 of the shell 1. The peripheral flat part of the top of the lid 2 will contact firmly with these elevations on the bottom of the casing of the adjacent condenser and allow circulation of air between consecutive units of these condensers when they are nested. This circulation conducts heat away from the terminals, otherwise some of the purpose of the hollow block 8 would be defeated.

The general form of the condenser is not made concavo-convex merely to permit stacking or piling of a series of these units, for obviously they could be stacked up just as well if they were disc-shaped. Having decided to make the terminals as large as possible, owing to their tendency to heat and having used the entire top and entire bottom of the condenser as the two terminals, we still have the problem of getting the current from these outside terminals to the ends of the sections 7 without long connections; for these connections would heat up. The best expedient is to bring down one of the terminals at the center to contact with the inner ends of the stacks and to shape the periphery of the shell or body 1 so that it practically touches the outer ends of the stacks. Obviously the center of the bottom will have to bulge away from the inner ends of the stacks, they being of opposite potential with respect to the bottom. Since the periphery of the shell 1 is brought clear into the equator or central transverse plane of the condenser taken as a whole, the periphery of the top must be spaced from the outer ends of the stacks, to provide room for insulation between it and the body 1. A

further need is to make the inside curvature of the hollow top greater than the outside curvature of the bulged bottom, so that the condensers still can be stacked. Since the bulge of each successive unit is largely within the hollow of the preceding unit, the over-all length of a plurality of the condenser units is much smaller than if the casings were relatively flat or shallow.

Of course the layers of metal foil and mica in the units 11 can be arranged in any manner, and the units 11 grouped and connected as required.

Currents of very high frequency, such as the ones that the herein described condenser is adapted to receive, have certain attributes and conform to definite laws; and these laws are quite at variance with those which apply to low frequency alternating currents.

First: They follow the outside of a conductor. Second: They do not penetrate even a slight depth of solid metal if any outside path even of considerable length offers itself. Third: They do not follow into re-entrant angles in the surface of a conductor, such as those that frequently occur at joints.

The following by such current of the outside of a conductor does not take place in such a simple manner as would be expected at first sight, for the current may not distribute itself all over the superficial area of the conductor. Assume that the current were passed longitudinally through a metal bird cage or through a cylinder of netting, such as is placed around small trees, the current would not distribute itself completely around the surface of each individual wire, but would travel along one side only of each wire and that side would be the outermost one with respect to the longitudinal axis of the cage or cylinder of netting. Assume again that such a current were being passed longitudinally through a sheet metal cone, say from the edges of the base to the apex (the cone, of course, having two surfaces, one inside and one outside with respect to the longitudinal axis), the current would not split, half of it travelling along each surface, but all of the current would follow along the outside surface, while none of it would utilize the inside surface.

With respect to solid metal, the current does not even penetrate a very thin piece of sheet metal if a surface path that is not of extreme length and complication offers itself. Furthermore, the width of the surface path is of some importance, for an apparently crooked or curved path may offer scarcely any resistance if the path is quite wide so as not to require any great surface density per unit of area.

The aversion of these currents to flow into re-entrant angles, such as those found adjacent carelessly designed joints, is well illustrated by Litz wire, for the current in-

stead of following any given surface after the wire passes into the body of the platted mass of wires, simply leaps across the intervening space and takes up its path along the surface of some other wire which happens to be at the surface of the platted mass. Such currents heat up such wire excessively.

Assume that the path of a high frequency current is at right angles to the contact joint 10 between two conductors, the joint being so shaped as to make a deep recess, depression or crotch where the two bodies join, then the current instead of following all the way into the bottom of the recess and coming up at 15 the opposite side, usually leaps from edge to edge so to speak, penetrating the intervening atmosphere; and this results in considerable heating effect. In other words, the current has a tendency to follow along a tangent 20 to the general surface rather than to follow in detail into re-entrant angles and depressed irregularities.

Assume that such a current were being transmitted along a complicated mass of 25 conducting wire cable or a maze of wire platted Litz fashion, the mass of wires, however, having a definite boundary and a fairly uniform cross section, such as circular, then it would be found that all of the interior portions 30 of the wires are quite useless as conductors, for even if from time to time a given interior wire came to the surface the current would all be localized along the exterior of the cylindrical mass following any portion 35 of a wire that was exterior with respect to the central axis and jumping from that portion to some other wire that had a part on the exterior at any point where the first mentioned wire passed to the interior. We have 40 taken account of these principles for our invention.

In the development of this invention provision for the path of the current was not limited to merely enlarging the terminals 45 for the same. The certainty with which high frequency currents seek the outside of any conductor was recognized. Referring to the diagram, Figure 6, attention is called to the median line 40-41. The current in travelling along various paths to get through one or several condensers progresses in a general direction parallel to the line 40-41 and in traversing a mass of metal such as the top 50 2 it will follow along the surface 42 rather than the surface 43 because 42 is "outside" 55 with respect to the line 40-41. Top 2 has two surfaces 42 and 43 and since it is a fact that these high frequency currents travel on the surface of a mass of metal instead of 60 through the interior of the same, it follows that the path will be either 42 or 43. But, looking at Figures 1 and 2, it will be seen that the cross section of the general path of the current into the condenser by means 65 of terminal 2 is coincident with the cross-sectional area of the entire condenser. Look-

ing at Figure 6 and remembering that this kind of current will travel along the "outside" surface of a hollow conductor, it will be seen that the current in passing from the periphery to the center of the top 2 will take 70 up its position "outside" with respect to the line 40-41, this "outside" being surface 42.

The entire path of the current is along surface 42 to plate 16; from plate 16 through flanges 17 to conducting plates 15 placed adjacent the innermost element of each stack 7; through the stacks 7 (so to speak) as indicated by arrows 44 to the conducting plates 20 and the current follows the plates 20 till "solid" metal is reached where 20 is clamped 80 between ring 22 and bottom 1. That is, in between the parts 22 and 1 conductor 20 has neither surface free. But referring to the plan, Figure 1, it will be seen that the plates or strips 20 occupy a small part only of the 85 periphery of the shoulder 24 of the base 1. At all other points on this shoulder there is an open space between shoulder 24 and ring 22, as seen in the right hand half of Figure 6, equal to the thickness of the strips or plates 90 20. In these open spaces the current travels across the surface of the shoulder as indicated by the line 45. Upon reaching the rim or flange 21 it passes up the inner surface 46 of the same and then down the outer surface 47 95 of the flange 21 to the surface 48 of the flange 18 of the next adjacent condenser, thence to surface 42 of the next condenser and so on. The surfaces traversed by the current are all indicated in heavy black lines.

Here several questions are pertinent. Why does not the current pass directly through the casing 1 when it reaches that part of the strip 20 that is clamped between ring 22 and casing 1? And when it reaches flange 21 why does it not pass directly through the flange. In both instances the reason is that a long surface path is preferable to or offers less resistance than a much shorter path through solid metal. Why is not the strip 20 always turned the other way so as to contact with the upper edge of flange 21, as illustrated in Figures 7, 8 and 9? Because of various structural difficulties such as interference with the tightness of gasket 31. Also, because a short 115 crooked path of large width or area such as the 46-47 path offers relatively little additional resistance provided the current does not have to cross through a thickness of metal. Reviewing the entire path of the current as 120 shown by the heavy lines of Figure 6 it is seen that at no point is the current forced to cross or penetrate any thickness of metal, not even the thin strips 15 or 20.

Referring more particularly to Figures 7, 125 8 and 9 it will be noted that strip 20 is replaced by a strip 51 which passes above the ring 22 instead of below and passes beneath the rubber gasket 31. It is fast to the up-standing rim 21 by means of a thin strip of metal 52 held by means of screws 53.

Figure 9 shows how the current follows the path 54, 55 and 47 when using the strip 51, instead of the path 45, 46 and 47 when using the strip 20.

5 Of course, strictly speaking, the current does not flow through the sections 7 of the condenser, but flows only through the metal parts united to the terminals of the condenser sections 7.

10 The invention is not limited to the modifications described above for illustrative purposes but numerous changes can be made without exceeding the scope of the following claims.

15 Having described my invention, what I believe to be new and desire to secure and protect by Letters Patent of the United States is:—

20 1. A condenser comprising a plurality of radially arranged sections and a casing with portions of its area adapted to serve as terminals, one part of the casing being shaped to make direct contact with the common center of the sections, and another part thereof shaped to make contact with the outer ends of the sections.

25 2. A condenser comprising a plurality of groups of dielectric and conductive elements, and an enclosing casing having large portions 30 of its surface forming two conducting areas, one of said areas curved inward to make direct contact with one end of each group and the other of said areas curved to make direct contact with the opposite end of each group.

35 3. A condenser comprising a casing having a flat side with a centrally located convex area, and a flat side opposite to the first mentioned side having a concave area of such relative contour that a duplicate condenser can 40 rest with its convex area within said concave area with the flat side of the duplicate condenser contacting with a flat side of the first mentioned condenser.

45 4. A condenser casing as stated in claim 3 in which one of the flat sides is provided with slight elevations to provide a passage for the circulation of a cooling medium between the first mentioned condenser and the duplicate condenser.

50 5. A condenser comprising a casing, a central block therein and sections of condenser elements abutting the central block, said block being hollow and open to the exterior of said casing.

55 6. A condenser comprising a casing, a central block therein and sections of condenser elements engaging the central block, the casing being curved inward to serve as a terminal for said stacks, and comprising a means for ventilation of the central block.

60 7. A condenser including a body, a surrounding frame to compress the body and a casing to enclose the body, the casing being separable from the frame for assembly pur-

poses and fastened firmly to the frame while the condenser is in use.

8. In a condenser the combination of a central abutment, a plurality of sections of dielectric and conductive elements arranged 70 radially of the abutment, insulating blocks between the sections and the central abutment, a conducting plate between each section and its respective insulating block, a terminal plate on top of the abutment adapted to contact with all the conducting plates. 75

9. A condenser comprising radially arranged sections, a central hollow block at the inner ends of said sections, a concave terminal contacting at its center with the inner ends of said sections, a convex terminal contacting at its periphery with the outer ends of said sections, an insulating ring extending from the periphery of the concave terminal to the outer ends of said section, and a cylinder of insulation extending from the center of the convex terminal to the inner ends of the sections, said hollow block, concave terminal, convex terminal, insulating ring and insulating cylinder completely enclosing said 90 condenser. 95

10. A condenser comprising condenser sections arranged radially around a hollow block, a casing arranged for stacking a plurality of such condensers, a passage through 95 the hollow block to register in consecutive condensers of a stack, forming a continuous passageway.

11. A plurality of condensers in containers, a passage through the body of each of said 100 containers, means for stacking said containers to register said passages with each other, so that a continuous passageway is formed.

12. A condenser adapted for use in radio frequency circuits, comprising a casing member surrounding a plurality of radially disposed stack sections, metal end closures for the casing member, each closure member forming one terminal of the condenser and having a relatively large surface, one of said 105 closure members being connected to each of the inner ends of the stack sections, and the other end member being connected to each of the outer ends of the stack sections, whereby high frequency currents will pass without 110 heating the condenser or terminals. 115

13. A high frequency condenser having an insulating casing member surrounding a plurality of radially disposed stack sections, metal end plates for the insulating member, each 120 end plate forming one terminal of the condenser and having a relatively large area, one of said end plates being connected at its central portion to each of the inner ends of the stack sections, the other end plate 125 being connected at its peripheral portions to each of the outer ends of the stack sections, whereby high frequency currents will pass without causing heating of the condenser or terminals. 130

14. A high frequency condenser having a tubular casing member of insulating material enclosing a plurality of radially disposed stack sections, metal end plates for the casing member, each plate forming one terminal of the condenser and having a relatively large surface, one of said end plates being connected at its central portion with each of the inner ends of the stack sections, the other end plate being connected at its peripheral portions to each of the outer ends of the stack sections, whereby radio frequency currents will pass without causing heating of the condenser or terminals.
15. In testimony whereof we affix our signatures.

ALEXANDER NYMAN.
WILLIAM DUBILIER.
